UNITED STATES PATENT OFFICE

159,691

DISPENSER FOR STAMPS OR THE LIKE

Ralph W. Stayton, Albany, Calif., assignor to Yuletide Bonus Stamp Company, Albany, Calif.,
a corporation of California

Application January 24, 1948, Serial No. 144,014

Term of patent 14 years

(Cl. D80—9)

To all whom it may concern:

Be it known that I, Ralph W. Stayton, a citizen of the United States and a resident of Albany, county of Alameda, and State of California, have invented a new, original, and ornamental Design for a Dispenser for Stamps or the like, of which the following is a specification, reference being had to the accompanying drawing forming part thereof.

I claim:

The ornamental design for a dispenser for stamps or the like, substantially as shown.

RALPH W. STAYTON.
